UNITED STATES PATENT OFFICE

GRIFFITH M. LEWIS, OF WATERVLIET, NEW YORK, ASSIGNOR TO WILCOX & GIBBS
SEWING MACHINE CO., OF NEW YORK, N. Y., A CORPORATION OF NEW YORK

SEWING MACHINE TAPE GUIDING MEANS

Application filed October 29, 1925. Serial No. 65,663.

This invention relates to sewing machines and particularly to tape guiding and inserting means applicable to sewing machines generally but especially designed for use in conjunction with the sewing machine commercially known as the Willcox & Gibbs Sewing Machine Company's "Flatlock machine", partly shown for example in the patents to Stockton Borton 1,041,574, and to A. A. Merritt 1,041,652, both dated October 15, 1912, and producing the seam of said Borton's Patent 883,614 dated March 31, 1908, commercially known as the "Flatwork seam".

Generally in the manufacture of under-wear from knitted fabric, seams having longitudinal elasticity are desirable. But there are some seams in the seaming where such elasticity is objectionable and detrimental in admitting of undue stretching and consequent distortion, misshaping and misfitting of the garment particularly after the garment has been in use. Instances of this are French collarettes where the seam which fastens the collarette into the neck opening of the body of the garment runs across the wales of the collarette; and shoulder seams which run across the wales of the fabric of the body of the garment. For the purpose of rendering such seams non-elastic it has been heretofore proposed to incorporate a non-elastic tape in the seam during its process of formation, such tape acting to prevent longitudinal as well as cross-wise stretching and to generally strengthen the seam.

An object of the present invention is the provision, in conjunction with a sewing machine capable of forming a suitable seam for knitted underware, of tape guiding and inserting means capable of being quickly and readily thrown into and out of operation by the machine operative without materially interfering with or interrupting the normal and regular running of the machine, where-by the operative may control and effect the

insertion of the tape in such of the seams, or at any points in seams, where it may be desirable, and accomplish this without materially lessening the speed of operation or production as compared to the running of the machine without the provision of such tape guiding means.

The aforesaid and other objects and advantages are attained by what is now believed to be the preferred embodiment of the invention illustrated in the accompanying drawings, wherein

Fig. 1 is a perspective view of a sewing machine equipped with the tape guiding and inserting means;

Fig. 2 is a front elevation of the work-arm of said sewing machine with parts in section;

Fig. 3 is a top plan view and Fig. 4 a bottom plan view of the cover plate of the work-arm having applied thereto the tape guiding and inserting means;

Fig. 5 is a transverse section on line 5—5 of Fig. 3;

Figs. 6 and 7 are top and bottom detail perspective views of the tape guide;

Fig. 8 comprises a collection of detail perspective views of the cover plate of the work-arm and some of the parts associated therewith;

Fig. 9 is an enlarged detail view from the right side of the garment, or what is the upper side of the seam in its process of formation, showing one way of inserting tape in the under or wrong side of a seam as accomplished by the means of the present invention; and

Fig. 10 is a diagrammatic view through the seam of Fig. 9, further showing approximately the relationship of the joined edges of the fabric, the tape insertion and the threads of the seam.

In the drawings, the tape guiding and inserting means are illustrated in conjunction with a "flatlock machine" such as hereinbe-

fore mentioned. The hollow machine frame or casing shown in Figs. 1 and 2, includes hollow standards 20 and 21 at opposite ends of said frame connected by a hollow bridge portion 22. The feed-off-the-arm hollow work-arm of the machine includes an upper part 23, extending horizontally outward from and forward as a continuation of the upper end of the hollow standard 21, a vertically depending part 24 (only a fragment of which appears in Fig. 1), and a horizontal work-supporting part 25 having a free end off which the work is fed. At its upper end the hollow standard 20 extends forward and constitutes the head 26 of the machine which partly overhangs the end of the horizontal work-supporting part 25 of the work-arm. At the free end of said part 25 of the work-arm there is a throat-plate or cloth-plate 27 having therein suitable slots in and through which operate the forward or fulling feed dog 28 and the rearward or stitch feed dog 29 in engaging and feeding the fabric or work along said part 25 of the work-arm and toward and off the free end thereof.

30 is a presser foot positioned above the throat-plate 27 and supported from the head 26 of the machine frame in a manner to be 30 yieldingly pressed downward into engagement with the fabric or work passing thereunder. The presser foot shown is of the type having a slot 35 at its forward end in which upturned edges of fabric are guided 35 to trimmer blades the cutting edges of which coact at the rear end of said slot to trim the fabric edges before they are sewed together by the needles and corresponding parts of the stitch-forming mechanism. One of said 40 trimmer blades, shown at 31 in Fig. 1, is preferably fixed to the presser foot.

A removable cover 32 for the part 25 of the work-arm has at one end a bevelled lip 33 adapted to engage in a correspondingly 45 undercut recess (Fig. 2) in one end of the throat-plate 27, and at its other end said cover is secured in place by a spring-actuated bolt latch 34 having a conical point adapted to seat in a conical depression in the wall 50 of the upright part 24 of the work-arm. By an upward pull or lift on this cover-plate 32 at its forward end where the latch bolt 34 is located, said bolt will be readily disengaged from its seat and the cover-plate thus 55 released for removal by disengagement of the lip 33 from the recess in the edge of the throat-plate.

The parts as thus far described in the detailed description are substantially the same 60 as in the aforesaid Flatlock machine and patents thereon.

The upper surface of the arm cover-plate 32 is formed with a flattened portion 40 near one end thereof, with a groove 41 extending 65 longitudinally of the cover-plate from said

flattened surface portion 40 to the other end of the plate, and with an opening 42 through the plate at the bottom of said groove. A tape guide, hinged to the cover-plate so as to be movable to a lowered active position or 70 to be raised to an inactive position, includes as part thereof a hinge comprising leaves 43 and 44, the leaf 43 of which fits against and is secured by screws to the flattened surface portion 40 of the cover plate. A flattened 75 tubular tape guiding member 45 may be formed by bending over toward each other the two side edges of a strip of sheet metal, these edges preferably being left slightly spaced from each other to provide a narrow 80 slot 46 extending lengthwise of this guiding member and through which slot the tape and its movement may be observed. At its delivery end, the member 45 extends beyond the end of the cover plate 32 when in its active 85 lowered position and terminates close to the forward end of the presser foot 30, as shown in Fig. 2. At its other end the tubular guiding member 45 is rigidly secured to the leaf 44 of the hinge by a strap 47 and by soldering. 90 A reinforcing metal strip or bar 48 secured along the under side of tubular member 45 in suitable manner, as by soldering, is of such dimensions as to fit in the groove 41 and thus also serve to accurately position and 95 hold the tape guide in its proper position and alignment with relation to the stitch-forming mechanism and particularly the needles thereof. A detent or latch stud 49, rigidly secured to bar 48, as by riveting or soldering 100 in an opening through said bar, has a notch 50 in one side thereof and a beveled outer end 51, and is positioned to project through the opening 42 of the cover plate 32 when the tape guide is in its lowered active position. A detent or latch bar 52 slides in a 105 groove across the under side of cover plate 32 (Figs. 2 and 5), and has an opening 53 (Figs. 5 and 8) adapted to register with opening 42 of said plate and be entered by the latch-stud 49. A plate 54, secured by 110 screws to the under side of cover-plate 32, holds the latch-bar 52 in its groove, and a stud 55 passing through a slot 56 in said latch-bar limits the sliding movement of the latter. The edge of cover-plate 32 which is toward the main portion of the sewing machine, is recessed or cut away at 60 to receive the bowed spring 61 made of flat strip spring metal and having an elongated notch 62 at each end and held in place by screws 63, 63 passing freely through said notches into the 115 edge of the cover plate 32. At its middle said spring 61 is riveted or otherwise secured to the bent-over outer end of the latch-bar. 65 is a leaf-spring riveted or otherwise secured at one end to the under side of the leaf 44 of the hinge, said spring extending 120 parallel to and beneath the bar 48 and being 125

of a width to fit in the groove 41 of the cover plate 32.

As shown in full lines in Fig. 1, and also in Figs. 2, 3, 4 and 5, the tape guide is in its lowered or active position and so held by the latch or detent means with the leaf-spring 65 under compression in and against the bottom of the groove 41 (as shown in Fig. 2), the bar 48 also fitting in said groove approximately from end to end thereof; the latch-bar 52 is held in engagement with the notch 50 of the latch-stud 49 by the tension of spring 61; and the free end of the tape guiding member 45 terminates close to the forward end of the presser foot. Tape *a* drawn from a suitable source of supply from above, passes downward (as shown in Fig. 2) into the open receiving end of the tubular guiding member 45, through the same and from its delivery end where the tape is applied against the under side of the fabric, which in passing under the presser foot first passes over and above said tape guiding member at the delivery end of the latter. The feed dogs 28, 29 (Fig. 2) of the sewing machine, upwardly engage the fabric and tape from below, feeding the same stitch by stitch and at the same time drawing tape from its source of supply through the tape guiding tubular member 45.

As diagrammatically shown in Fig. 9, the edges of two pieces of fabric *b* and *c* are shown as having been joined by a flatlock seam such as hereinbefore mentioned, including four parallel lines of stitches made by four needles, and with tape *a* applied to the under side of the fabric across the abutted joined edges thereof, said tape being of a width less than the distance between the outside needles, whereby the threads of the seam or stitches extend across both edges and the outer surface of the tape, thus substantially enclosing or encasing the tape. But if desired, the tape may be wider than the distance between the outside needles so that the stitches made by all four needles will pass through the tape.

In the manipulation and guiding of the fabric along the work-arm to the presser foot, the right arm of the operative is passed under the horizontal portion 23 and along the work supporting part 25 of the work-arm so that the spring 61 of the latch of the tape guide is readily accessible to the operative's right hand. When the operative reaches a seam or portion of a seam to which it is not desired to apply the tape, she presses against spring 61 with the thumb of her right hand, moving the detent-bar 52 inward against the tension of said spring until said bar disengages the notch 50 of the detent-stud 49, whereupon the spring 65 flips the tape guide upward on its hinge to a position approximately shown in dotted lines in Fig. 2, with the tape leading from the end of the guide downward in an

inclined path (approximated in dotted lines in Fig. 2) to the work under the presser foot, this path of the tape leading through the slot of the presser foot and between the cutting edges of the trimmer blades with the result that the tape is clipped or severed leaving a loose end thereof extending beyond the end of the tape guide ready for insertion under the presser foot in the next operation of applying tape. But if preferred, the operative may herself clip the tape at such length as desired between the uplifted delivery end of the tape guide and the work. While the tape guide is not being used, it may if desired be swung back completely out of the way to the upright position, in which it is shown in dotted lines in Fig. 1, approximately parallel to and in line with the vertically depending part 24 of the work-arm and to the rear of said part when looking in the direction of feed. When needed, the tape guide can be quickly pressed down to its active position and will be automatically engaged and held by the latch means. The end of the tape left extending beyond the end of the guide member by the previous clipping can be readily and accurately positioned by lifting the presser foot if necessary, and the machine then operated to form the seam with the tape inserted or incorporated therein. Such throwing of the tape guide out of and into action can be quickly accomplished with very little interruption in the normal running of the machine.

When the machine is being used on work of a character not requiring use of the tape, the cover plate 32 with the tape guiding means mounted thereon may be readily replaced by a similar plate having no such means.

What is claimed is:

1. In a sewing machine, the combination of stitch-forming elements, a presser foot, a work-arm having an approximately horizontal work-supporting part free at one end, work-feeding means for feeding work along said work-supporting part of the arm past the presser foot and stitch-forming elements, and tape guiding means mounted on said work-supporting part of the work-arm in advance of said presser foot for guiding tape at both edges thereof to position to be applied to the surface of fabric or work and secured to the work by stitches formed by said stitch forming elements, said tape guiding means being movable to an inoperative position without detachment from the machine and without movement to a non-operative position of the part on which said tape guiding means is mounted.
2. In a sewing machine, the combination of stitch-forming elements, a presser foot, a work-arm having an approximately horizontal work-supporting part free at one end at which said stitch-forming elements and presser foot operate, work-feeding means for feeding work along said work-supporting

part of the arm past the presser foot and stitch-forming elements and off the free end of said part of the arm, and tape guiding means mounted on said work-supporting part of the work-arm in advance of said presser foot for guiding tape at both edges thereof to position to be applied to the surface of fabric or work and secured to the work by stitches formed by said stitch-forming elements, said tape guiding means being movable to an inoperative position without detachment from the machine.

3. In a sewing machine, the combination of stitch-forming elements, a presser foot, a work-arm having an approximately horizontal work-supporting part free at one end, work feeding means for feeding work along said work-supporting part of the arm past the presser foot and stitch-forming elements, a detachable and removable plate along said work-supporting part of the work-arm in advance of the presser foot, and tape guiding means positioned close to the presser foot and mounted on and removable with said plate, said guiding means operating to guide tape to position to be applied to the surface of fabric or work and secured to the work by stitches formed by said stitch-forming elements and being movable to an inoperative position without detachment from said plate on which it is mounted.

4. In a sewing machine, the combination of stitch-forming elements, a presser foot, a work-arm having an approximately horizontal work-supporting part free at one end at which said stitch-forming elements and presser foot operate, work-feeding means for feeding work along said work-supporting part of the arm past the presser foot and stitch-forming elements and off the free end of said part of the arm, a detachable and removable cover-plate along said work-supporting part of the arm in advance of the presser foot, and tape guiding means positioned close to the presser foot and mounted on and removable with said cover-plate, said guiding means operating to guide tape to position to be applied to the surface of fabric or work and secured to the work by stitches formed by said stitch-forming elements and being movable to an inoperative position without detachment from said cover-plate on which it is mounted.

5. In a sewing machine, the combination of means for trimming edges of fabric, stitch-forming mechanism for sewing together the edges of fabric after they are trimmed, and tape guiding means operating to guide tape to position to be applied to the surface of said fabric where said trimmed edges join each other and secured to the work by a plurality of spaced lines of stitches formed by said stitch-forming mechanism and which stitches also pass through both of said trimmed edges, said tape-guiding means

being so mounted on the machine as to be movable from an operative to an inoperative position without detachment from the machine and without movement to a non-operative position of the part on which said tape guiding means is mounted.

6. In a sewing machine, the combination of means for trimming edges of fabric, stitch-forming mechanism for sewing together the edges of fabric after they are trimmed, and tape guiding means operating to guide tape to position to be secured to the work by a plurality of spaced lines of stitches formed by said stitch-forming mechanism and which stitches engage both of said trimmed edges, said tape guiding means being mounted on the machine so as to be movable while on the machine from an operative position, in which the fabric to which the tape is to be secured passes over the delivery end of the guide, to an inoperative position.

7. In a sewing machine, the combination of a presser foot having a fabric guiding slot extending rearward from the forward end of said foot, trimming means operating approximately horizontally in said slot to trim fabric fed along the slot, stitch-forming elements positioned to act on the fabric after it passes the trimming means, work-feeding means for advancing the fabric to said trimming means and stitch-forming elements, tape guiding means acting in its normal position to guide tape to position to be secured to the work by stitches formed by said stitch-forming elements as the work is advanced by said feeding means, releasable detent means for holding said tape guiding means in normal position, and means acting upon release of said detent means to move said tape guiding means from normal position to one in which the tape is positioned in the path of the trimming mechanism and severed thereby.

8. In a sewing machine, the combination of stitch-forming elements and fabric trimming means, work-feeding means for feeding work to said stitch-forming elements and trimming means, tape guiding means acting in its normal position to guide tape to position to be secured to the surface of fabric, trimmed by said trimming means, by a plurality of spaced lines of stitches formed by said stitch-forming elements as the work is advanced by said feeding means, said tape-guiding means being movable from its said normal position, in which it guides the tape clear of the trimmer means and in which the fabric to which the tape is to be secured passes over the delivery end of the guide, to a position in which the tape is presented in the path of the trimming means and severed thereby.

9. In a sewing machine, the combination of a presser-foot having a slot and associated trimmer means acting in said slot, stitch-forming elements, a tape guide mounted on

the machine with its delivery end in advance of the presser-foot to guide tape beneath said foot and to position to be secured to the surface of fabric, trimmed by said trimming means, by a plurality of spaced lines of stitches formed by said stitch-forming elements, said tape guide being movable to change the position of its delivery end from its said normal position, in which it guides the tape clear of the trimmer means and in which the fabric to which the tape is to be secured passes over the delivery end of the guide, to a position in which the tape leading therefrom to the work is brought into the path of the trimming means and severed thereby.

said work-supporting part of the arm past the presser-foot and stitch-forming elements, and tape guiding means mounted on said work-supporting part of the work-arm in advance of said presser foot and adapted to guide tape to position to be applied to the under surface of fabric or work passing through the machine and to be secured to said fabric by stitches formed by said stitch-forming elements and which stitches engage each of two edges of said work or fabric being secured together, said tape-guiding means being movable to an inoperative position without detachment from the machine and without movement to a non-operative position of the part on which said tape guiding means is mounted.

65 13. In a sewing machine, the combination of stitch-forming elements, a presser foot, a work-arm including an approximately horizontal work-supporting part having a free end at which said stitch-forming elements

16. In a sewing machine, the combination of stitch-forming elements, a presser foot, a work-arm having an approximately horizontal work-supporting part free at one end, work-feeding means for feeding work along

said work-supporting part of the arm past the presser-foot and stitch-forming elements, and tape guiding means mounted on said work-supporting part of the work-arm in advance of said presser foot and adapted to guide tape to position to be applied across the medial line of a seam comprising stitches formed by said stitch-forming elements and engaging said tape at both sides of said medial line, said tape-guiding means being movable to an inoperative position without detachment from the machine and without movement to a non-operative position of the part on which said tape guiding means is mounted.

17. In a sewing machine, the combination of stitch-forming elements, a presser foot, a work-arm having an approximately horizontal work-supporting part free at one end, work-feeding means for feeding work along said work-supporting part of the arm past the presser foot and stitch-forming elements, and tape guiding means mounted on said work-supporting part of the work arm and including a tubular guiding member terminating close to the presser foot and movable from said position to an inoperative position without movement to a non-operative position of the part on which said tape guiding means is mounted.

18. In a sewing machine, having an approximately horizontal work-supporting arm, the combination with stitch-forming elements for joining together the edges of fabric, of a tape guide in the form of a flattened tube extending along and attached to said arm in advance of said stitch-forming elements and having its delivery end on both sides of the line of seam, said tape guide being moveable from an operative position to an inoperative position without movement to a non-operative position of the part to which said tape-guide is attached.

19. In a sewing machine, the combination with stitch-forming elements for joining together edges of fabric, of a tape guide in advance of said stitch-forming elements and whose delivery end underlies the fabric and extends across the line of seam, said tape guide being moveable from an operative position to an inoperative position without requiring movement of another part of the machine to a non-operative position.

20. In a sewing machine, the combination with stitch-forming elements for joining together the edges of fabric, of a tape guide supported in such manner as to be capable of occupying two positions, one operative and the other inoperative with respect to said stitch-forming elements, and of being quickly shifted from one position to the other without requiring corresponding movement of another part of the machine, the delivery end of said guide underlying, when in its opera-

tive position, the fabric whose edges are to be joined.

In testimony whereof I have signed this specification.
